VARIABLE INDUCTANCE TUNER

Sidney Y. White, Wilmette, Ill., assignor to Victor S. Johnson, Chicago, Ill.; Alex Thomson administrator of said Victor S. Johnson, deceased

Application December 8, 1942, Serial No. 468,195

7 Claims. (Cl. 171—242)

1

This invention relates to radio apparatus, and is particularly, although not exclusively, concerned with mobile radio apparatus suitable for meeting the exacting requirements of military service on land, at sea, and in the air.

Such apparatus may be carried on a wide variety of vehicles such, for example, as a truck, a tank, or a naval airplane catapulted from a cruiser. It may be subjected, therefore, to violent shock and to extreme and protracted vibration. Again it may be carried on the back of a soldier.

Such apparatus may be used in every condition of climate and weather to be found on the face of the earth, and in every season. It may be exposed to dust, mist, rain, sleet and snow from the air, and to mud and oil spray thrown up from roadways. It may be exposed to radical and abrupt changes of temperature, humidity and air pressure by being carried in the space of only a few minutes from a tropical desert into the stratosphere, or vice versa.

It is often desirable that many communication channels be made available, and that the distance at which a transmitter may be received shall be limited, in order that the same communication channels may be used in different regions without the possibility of mutual interference, and also as a safeguard against listening in by the enemy. For these reasons, among others, it is often desirable that apparatus for military use be designed to operate in the ultra-high frequency range. The ultra-high frequency range has important uses for non-military as well as military purposes, but its use imposes severe requirements.

The solution of the above problems is dealt with comprehensively and in detail in the present application and in divisions thereof, features originally shown but not now claimed herein being disclosed and claimed in the following divisional applications:

Radio apparatus, Ser. No. 506,372, filed October 15, 1943, Patent #2,407,359, dated September 10, 1946;

Radio apparatus, Ser. No. 725,685, filed January 31, 1947;

Electrical condensers, Ser. No. 506,374, filed October 15, 1943;

Method of lining up uncontrolled tuned radio apparatus, Ser. No. 506,375, filed October 15, 1943; Patent No. 2,422,331, dated June 17, 1947;

Method of making inductance coils, Ser. No. 717,139, filed December 19, 1946;

Method of temperature compensating tuned circuits, Ser. No. 506,377, filed October 15, 1943;

Patent No. 2,407,360, dated September 10, 1946;

Electric condensers, Ser. No. 551,805, filed August 30, 1944;

Precision radio apparatus, Ser. No. 711,437, filed November 21, 1946;

2

Precision radio apparatus, Ser. No. 711,438, filed November 21, 1946.

A complete disclosure of illustrative apparatus embodying the invention may be found in Patent No. 2,407,359.

The present application has to do particularly with a variable inductance tuner per se, an important object being to provide a straight line tuning curve through a very extensive range.

A further object is to provide a unit of the kind referred to in the preceding paragraph in combination with means for materially altering the slope of the tuning curve without changing the straight line character thereof.

It is a still further object to provide a core operator and carrier which can be depended upon to determine and maintain a predetermined relation of the coil to the core and dial.

Fig. 1 is a fragmentary view showing the thrust rod and tuning core assembly;

Fig. 2 is a detailed sectional view showing a fragment of the structure shown at the left-hand end of Fig. 4 together with fragmentary portions of associated parts.

Fig. 3 is a top plan view of a coil and condenser supporting plate employed in the transmitter and in the receiver;

Fig. 4 is a sectional view of the supporting block shown in Fig. 3, taken on the line 4—4 of Fig. 3 looking in the direction of the arrows;

Fig. 5 is a sectional view of the block shown in Figs. 3 and 4 taken upon the line 5—5 of Fig. 4, looking in the direction of the arrows;

Fig. 6 is an end view of the assembly shown in Fig. 14.

Fig. 7 is a rear end view of a modified form of coil and condenser assembly;

Fig. 8 is a view in side elevation of the assembly of Fig. 7;

Fig. 9 is a sectional view taken upon the line 9—9 of Fig. 7 looking in the direction of the arrows;

Fig. 10 is a rear end view of a further modified form of coil and condenser assembly;

Fig. 11 is a view in side elevation of the assembly of Fig. 10;

Fig. 12 is a sectional view taken upon the line 12—12 of Fig. 10;

Fig. 13 is a sectional view taken upon the line 13—13 of Fig. 12 looking in the direction of the arrows;

Fig. 14 is a sectional view similar to Fig. 12 showing a further modified form of coil;

Fig. 15 is a graph illustrating the various relationships of tuning core movement in mils to the frequency in megacycles of circuits tuned and controlled by various diameter cores;

Fig. 16 is a graph showing mils of core movement required to change the frequency one mega-

cycle in the range of 100 to 140 megacycles, for various coil and core combinations; and

Fig. 17 is a graph provided for use in explaining the alignment of the receiver and/or transmitter with the precalibrated dial.

Cores 12 and 12a are mounted upon a ceramic thrust rod 111 for cooperating with the respective windings 35, 28 and 10 in fixed positions longitudinally of the rod for controlling the tuning of the tuned circuit assemblies containing the windings in accordance with the longitudinal movement of the thrust rod 111.

The dial mechanism, which will be described at a subsequent point, is designed to operate the cores 12 and 12a longitudinally for effecting tuning. Operation of the thrust rod 111 from the dial mechanism is so contrived that no air leakage joints are formed in the housing 80, 82.

The thrust rod 111 is provided with an enlargement 111a which has a circumferential groove 129 formed in it, as viewed in Figs. 1 and 2. A hollow threaded cap 121 is impaled upon the enlargement 111a, and a resilient split ring 122 is caught within the groove 129 and captured within the cap 121. With the ring 122 thus captured within the cap 121, the cap 121 is threaded onto the cup 119 to force and maintain the left-hand end of the thrust rod 111 firmly against the base of the cap 119, so that the rods 111 and 115 are caused to move in unison as one unitary structure. The construction also serves to establish and maintain axial alignment of the rods 111 and 115.

At the rear or right-hand end of the rod 111, the rod has affixed to it a metallic cap 122a having a circumferential groove 123 which is adapted to be received between inturned fingers of the yoke 89 of the diaphragm 87. The cap 122a serves as a slide bearing for cooperating with the bushing 113. A metallic sleeve 123a fixed on the rod 111 serves as a slide bearing for cooperating with bushing 112.

The mounting of the cores 12 and 12a upon the rod 111 (Fig. 1) presents a difficult problem. A ferromagnetic core made up of small dust particles held together by a binder is decidedly fragile and readily tends to chip and crack, if any pronounced localized pressure is brought to bear on it. Anything in the nature of a forced fit on the rod is impracticable.

Cores may be molded on the rod, but great care must be employed that the many tons of pressure required to form the core to a homogeneous mass does not crack the ceramic rod.

Cementing the core on the rod offers the difficulty of lack of the extremely precise maintained position of the core because of cold flow and bad thermal expansion characteristics of the cement, and also its change with age. Cements have also marked erratic changes of dielectric constant with temperature, and since they would be fully in the field of the coil, if used to cement the core in place, would give rise to an undesired change in frequency with temperature. The mounting means shown in Fig. 1 overcomes these difficulties by holding the cylindrical core firmly between two shoulders which bear over the entire ends of the core, thus giving rise to no high unit pressures. The ceramic piece 111a establishes the distance of the core 12a from the end of the push rod 115, and while it may be made integral with the rod 111, due to manufacturing difficulties it may well be made as a separate piece cemented on as shown. Its ends are ground parallel to one another and normal to the axis, and care is taken

when cementing that these faces are maintained normal to the axis of the rod 111. Core 12a is then loosely slipped on the rod and the ceramic spacer 111b slipped on next. The outside diameter of this spacer is made slightly greater than the diameter of the core, since experience has shown that if the core rubs against the inside of the coil form some iron particles are rubbed off the core and permanently deposited on the inside of the coil form causing a change in frequency due to this wandering of the iron.

The next ceramic spacer 111c is then slipped on to establish a desired position of the mixer core 12 on the rod. Another ceramic spacer 111d is slipped over the rod subsequent to mixer core 12, and a metallic sleeve 123a is rather tightly fitted over the rod at that point to cooperate with a sleeve bearing 112 screwed into the partition 85. Another ceramic spacer 111e then determines the position of the core 12 which tunes the antenna circuit, and a ceramic spacer 111f determines the distance between the final core and the end cap 122a.

All of these cores and spacers are more or less loose fit on the rod 111, and they are maintained in relation by a thrust pressure developed by the spring washer 122b, which forces the whole assembly against the stop provided by the piece 111a. The end cap 122a which cooperates with the bearing 113 inset in the partition 85 is then forced on with some pressure and cemented in position.

The cement used to fasten on ceramic end cap 111a and metallic end cap 122a is out of the field of any coil, and if, due to cold flow or age this cement creeps slightly, say of the order of one-thousandth of an inch or so, this will be taken up by the spring washer 122b, and the cores will not be altered in their positions relative to the abutment shoulder of cap 111a. While all of the spacer sleeves are of predetermined lengths within reasonable tolerances, it will be observed that the most important core, namely, the core 12a, which cooperates with the oscillator coil, does not depend upon any spacer sleeve for its position, but abuts at all times against the shoulder of the cap 111a. This point is stressed for the reason that variations which are tolerable with respect to the cores 12 would be highly objectionable with respect to the core 12a. The diameters of the spacers 111c to 111f have been made smaller than the cores solely to save weight which might give rise to inertia effects when the apparatus is used in locations where marked vibration and shock are encountered.

While the rods 111, the spacers 111a to 111f, inclusive, the base plates 166 and the coil forms 173 have been described as of ceramic material, it is to be understood that this term is intended to comprehend other insulating materials which have been found suitable such as glass and quartz. Plastics in general of either the thermoplastic or thermo-setting type have been found unsuitable for this type of construction, with the possible exception of "Micalyx," due to their cold flow, their non-cyclic cubic change with temperature, and their often erratic changes of dielectric constant with temperature.

The rod 115 is thrust rearward by the dial mechanism, and in turn thrusts the rod 111 rearward with it against the predetermined, light, combined spring action of the bellows 114 and the diaphragm 87.

It is to be noted that core tuning, as distinguished from variable condenser tuning, may

conveniently be effected through limited travel of a thrust rod, as distinguished from operation of a rotary shaft, and, therefore, is well adapted for operation through air-tight connections as described. The fact that tuning is effected through operation of a thrust rod is, therefore, a very important factor contributing to the elimination of adverse humidity and pressure variations.

Referring to Fig. 7, the coil supporting form 173a is shown as comprising a generally cylindrical shaped tube composed of the same ceramic material of which the plate 166 is formed. The coil may be heated when applied to the coil form, so that it may develop tension through shrinkage as it cools. The coil form is also longitudinally slotted as at 176, the slot being tapered to accommodate the tongues 171 so that the slot 176 and tongues 171 provide means for locating the coil form in a definite position on the supporting plate 166. A material which will glaze is applied to the portions of the coil form and plate 166 which are to be brought into contact with each other and the members then baked to glaze the material which thereupon unites the supporting blocks and coil form into a unitary rigid stable assembly. The ceramic material is preferably of such a nature that its surface contains a large number of small particles which project beyond the general surface level and puncture the skin of the ribbon 175 in numerous places, thereby entirely preventing any slippage of the ribbon on the coil form. The result is that the coil is maintained tightly in engagement with the coil form at all times and does not change in shape due to any changes in temperature or humidity. In other words, the coil and coil form are, as it were, locked together throughout the full length of the coil and the size and shape of the coil remain at all times the same as those of the coil form. This arrangement obviates any non-cyclic variation in distance between one turn of the coil and another and also any non-cyclic variations in the diameter of the coil so that once the coil is wound, its inductance thereafter is not subject to non-cyclic variations due to temperature or aging. The ribbon of the coil is desirably a semi-elastic material such as sterling silver. Such material combines with high conductivity a softness permitting ready penetration by the coil form crystals and an elasticity capable of maintaining the required tension. Pure silver has been found unsuitable because it does not have the required elasticity.

Referring to Figs. 7 and 8, a powdered iron slug 15 is secured against the lower surface of the block 166 by means of a pair of screws 177 which pass through the slots 168. The inner face 178 of the slug 15 is arcuate in shape so that it may be moved inwardly into engagement with the surface of the coil form 173. The manner of adjusting the position of the slug 15 for controlling the slope of the tuning curve of the oscillator will be hereinafter described.

Referring to Figs. 7 to 9, the coil supporting form 173a, formed of ceramic material is glazed to the supporting block 166. The coil form 173a has a cylindrical exterior surface. In this case the oscillator winding 35 consists of three turns 194, 195 and 196, which are unequally spaced, the turns 196 and 195 which are first entered by the core 12a being spaced closer together than the turns 195 and 194. Each coil portion consists of a thin metallic ring 197 which may be of silver or other suitable metal, and whose inside diameter is

somewhat less than the outside diameter of coil form 173a. The ring 197 on one side is cut transversely, so that its ends 198 and 199 are spaced slightly apart when the coil has been slightly expanded and slipped along the coil form into position, after which its inherent resilience causes the coil to grip the outer surface of the coil form firmly and secure the ring in a definite predetermined position on the coil form in a position normal to the axis thereof. The end 199 of turn 194 is connected to the end 198 of turn 195 by means of a metallic connector 200 which is soldered to the coil ends (see Fig. 9). A similar connector 201 connects the end 199 of turn 195 to the end 198 of turn 196, so that the current in passing through the winding flows in the same direction through all the turns. The coil terminals 180, 189 and 191 are provided the terminals 180 and 189 supporting the condenser 60 and the projecting tongue 179 on the terminal 180 being soldered to the end 198 of turn 194. The tongue 179 formed on coil terminal 189 is soldered to the end 199 of turn 196, while the tongue 190 on terminal 191 is soldered to the end 198 of turn 195, the connection of tongue 190 to turn 195 providing the intermediate tap 53 (Fig. 1) on the oscillator coil 35. Coil terminals 180 and 189 are held to the plate 166 by headed screws 192, and terminal 191 is similarly held to plate 166 by screw 192. The manner in which this assembly produces SLF (straight line frequency) will be hereinafter described.

Referring to Figs. 10 to 13 another construction of winding for producing SLF is shown in which the ceramic coil form 173b is provided with two grooves 202 and 203 disposed normal to its axis, and the groove 203 being somewhat deeper than 202, as shown in Figs. 12 and 13. The winding has only two turns 194 and 196, each turn being formed of the metallic ribbon 175. The projecting tongue 179 of coil terminal 180 is soldered to the end 198 of turn 194 and the tongue 179 of terminal 189 is soldered to the end 199 of coil turn 196. The two turns are connected together by means of a thin metallic connector 204 which is disposed in a longitudinally extending groove 205 formed in coil form 173b, the groove 205 sloping inwardly in the direction of turn 196 as illustrated in Fig. 27. One end of connector 204 is soldered to the end 199 of turn 194 and the opposite end of connector 204 is soldered to the end 198 of turn 196 as shown in Fig. 13, so that the current passes through both turns of the coil in the same direction. The metallic ribbon is held under tension by the connector 204, which connector is prevented from rotating by the groove 205 in the coil form so that the inner surface of the ribbon is maintained at all times in firm engagement with the coil form. The center tap on the coil is provided by means of the tongue 199a on the center coil terminal 191, this tongue being soldered to the middle of the connector 204 as indicated in Figs. 10 to 12. It is thus seen that the illustrated arrangement provides an oscillator coil in which the turns are of different diameter and have no pitch, and also provides a ready means for tapping the coil at its midpoint.

The coil arrangement shown in Fig. 14 is generally similar to that shown in Fig. 12 and the corresponding parts are indicated by similar reference numerals. In this case the connector member 204a does not bear against the sides of the groove 205 in the coil form 173c. The ends of each coil turn are provided with a pair of projecting ears 206 which abut against the wall of

the groove 205 as shown. In securing the turns of ribbon to the coil form the ears 206 at one end of the ribbon are placed against the wall of groove 205 and the turn of ribbon wrapped around the coil form in the groove therein, whereupon the ribbon may be heated by an electric current from a suitable source to cause it to expand considerably in length whereupon the pair of ears 206 at the other end of the coil will be slipped into the groove 205 and the ribbon permitted to cool. The contraction of the ribbon will place it under tension and cause its interior surface to be pressed into firm engagement with the bottom wall of the groove in which it is seated.

In all of the tuned circuit assemblies described, other than that of Figs. 7 to 9, a ribbon having a thickness of about three mils and a width of fifty to seventy mils may be advantageously employed. These dimensions are cited by way of example, however, and not as defining practical limits.

The type of tuning employed is of the core type, and while ferrous cores will be mainly discussed, the conductive type core, as for instance silver or copper, may well be used in some applications.

The tuned circuit must, therefore, be designed with the requirements of core tuning in mind. It is basic, however, that before we can tune the circuit over a range, the circuit without such tuning means must in itself maintain a fixed frequency to a high order of accuracy. It must also allow trimming, tracking and aligning with a precalibrated dial having great length and accuracy of resetting. It must have no wiring at all.

The coil is first considered. Its design must allow use of one to four turns, for example. It must allow bringing out a tap to any turn or fraction of a turn. Its external tuned circuit must include a tuning condenser having minimum inductance, and the whole outside return loop must be minimized.

The concentration of over 90% of the inductance is actually in the coils of the tuned circuit assemblies described where it is capable of being acted on by a core.

The diameter of the coil is chosen to be about 405 mils in the present instance for use with a 375 mil core. Considerable difficulty is had in the ceramic art in making thin walled tubes beyond a certain minimum thickness of wall. Maximum tuning ranges obtainable with core tuning are reached where the core substantially fills up the coil, but it must still freely pass through the bore of the coil form. If we chose this same ratio with a 125 mil core, the wall thickness would be less than 5 mils, an impracticable figure for quantity production in the present state of the ceramic art.

The coil form is made with grooves for the conductor, to have the thick lands to support the thin grooves during firing, and also to guide in the winding.

Since the conductor chosen must have high conductivity, its thermal coefficient of expansion must also be high, at least two or three times that of the coil form. The wire must be wound under sufficient tension and have enough elasticity to cling to the form at the most adverse temperature.

The cross-section of the conductor is a very thin strap, rather wide. If large, round conductors are used, such as #14 round wire, the current tends to hug the coil form as it is the smallest diameter of the turn. Any good conductor has a large temperature coefficient of resistance,

however, and if the temperature be raised the resulting increased resistance causes a redistribution of the current, causing the diameter of the mean current path to be increased. This markedly increases the inductance, since diameter of the current path is square in the formula for the inductance coil, and great changes in frequency result.

By using a very thin strap of the order of three mils in thickness, this effect is minimized and a disciplined current path results. Instead of using pure silver, sterling silver is used for greater toughness and elasticity and may be wound on the form quite hot by passing a heavy current through it while winding, in which case it shrinks on the form. Tension may be used also, sufficient to stress it nearly half way to its elastic limit so it hugs the coil form like a rubber band.

Silver plated "Invar" or "Nilvar" used in large cross-section maintains its cross-section under temperature variation, but the current redistribution is the same as for pure silver, and it must be wound under tension and in general has no advantage over the thin sterling silver strap, which may be flattened wire.

It is of great advantage to use ceramics of the low loss type such as Alsimag 196 because of the presence on the surface of minute sharp crystal structures which apparently pierce the skin of any unhardened metal pressed firmly against them. Repeated temperature cycling of these coils from -40 to $+217^{\circ}$ F. show no creepage of the winding, since each unit length is captured by its adjacent crystals and held firmly in place.

The length of coil chosen must also depend in part upon the tuning curve desired and upon the length of core travel most easily obtained with a desirable dial mechanism. A coil 375 mils long, measured center of winding strap to center of winding strap gives an active core movement of about 250 mils for 25% tuning range.

In any coil to be used with a core the inside of the coil form must be left free to pass the core. Most methods of terminating coils use rivets, eyelets, or passing the conductor through holes in the form, all of which would interfere with core movement. Some structure outside the simple cylindrical coil form is, therefore, required. This takes the form of the plate or block 166 with its associated terminal blocks 180, 189 and 191.

The block 166 is preferably glazed to the coil form. Plastic cements are undesirable because of cold flow and change with age, but a good glaze in the joint fired at 1700° F. really makes the two pieces unitary.

There are numerous advantages in having a straight line relationship between the amount of displacement of a core which controls the frequency of a resonant circuit and the resonant frequency produced. For example, it may be desired to cause an increment in frequency of exactly one megacycle with a core movement of exactly 10 mils (.010"), and to have this relationship hold over as wide a tuning range as possible as, for example, from 110 mc. to 135 mc.

Among the advantages of such an arrangement are that the use of an essentially linear dial and movement is possible, and that it permits one resonant circuit to be readily tracked with another in cases where a definite relationship, such as a constant frequency difference, is to be maintained between the resonant frequencies of the two circuits. In tuning a circuit over this frequency range it has been found practically desirable, because of physical limitations, to arrange

for a total core movement of the order of $\frac{1}{4}$ inch, as giving the best balanced design in this instance.

Fig. 15 shows a generalized series of curves for the purpose of discussing design parameters in connection with the straight line frequency relationship. All curves except A have been displaced in frequency to avoid confusion.

If we consider the case where the coil is a two-turn, flat ribbon spiral and the coil is essentially square, i. e., its diameter and length are about the same, and if this diameter be about .410 inch, then we may make up a series of cores of different diameters and observe their effect. A core the diameter of a pencil lead, for instance, would give us curve E of Fig. 15, an S-shaped curve with no approximately straight section in the middle. Curve D represents a somewhat larger core with greater tuning range, but still no substantially straight portion in the center. A somewhat larger diameter gives us curve C having a small apparently straight portion, while further increase gives us curve B with a substantially larger central straight portion.

Curve A represents the largest practical diameter that can be conveniently produced commercially without forcing us to thin the walls of the coil from beyond practical limits. This might have an approximately straight line frequency over a tuning range of about 17% in the frequency range shown. This shows the principle that the last few percent in tuning range increase that we obtain by steadily increasing the diameter of the core shows up as substantially straight line frequency (SLF). A spirally wound coil in general does not give SLF. A coil stretched out over too much length is in general undesirable as the ends are too far apart physically, forcing the use of a long return path on the outside of the coil which gives us unwanted inductance in the tuned circuit, since only that portion of the wire in the circuit which is wound on the coil form will be affected by the core used, and any external inductance will lessen the tuning range and consequently the SLF range we may possibly reach.

The iron cores we have available at present that can be used in these frequency ranges consist in general of two types, the oxide type, and the carbonyl type consisting of spheres of the order of 5 microns in diameter, and often having differentiated internal structure. Either type, when insulated and compressed into a core by the use of a binding agent, has an apparent permeability of the order of 2 when used in circuits of this nature, and we often wish to extend the SLF portion of the curve to the maximum possible to be reached with this iron.

Curve A represents an actual case of the use of such cores, and as seen it covers a range of about 17% which is substantially straight line frequency. It will be noted that the abscissa shows a total core movement of about $\frac{1}{2}$ inch or 500 mils, and that the SLF portion covers approximately 200 mils in the center of the curve. Drawn to this scale the curve seems to be absolutely straight in the center portion, but it is actually continuously curved by a rather slight but important amount.

There are a minimum of four effects taking place as a ferrous core is introduced into such a coil for producing the curve A shown in Fig. 15. They are: the true permeability effect alone; the eddy current effect which tends to cancel the permeability effect; the fact that the core is a capacity by itself and is also effective in grad-

ually capacity coupling one part of the circuit to another; and a resistance loss which is present in all apparatus. The curves shown, therefore, are the result of summation of these four effects.

- 5 It has been found helpful to plot curve A again in Fig. 16 in a different manner. A rather simple way to look at SLF is to say that to advance one unit of frequency we must advance the core one unit of distance, and as long as this relationship is maintained we have SLF tuning. The curves of Fig. 16 have, therefore, been plotted with the ordinates representing the mils of core movement required to tune the circuit over one megacycle, and the abscissas representing a portion of the frequency spectrum we are investigating. Plotted this way curve A is shown as A' and forms a curve resembling a parabola. Curve A, Fig. 15, might be considered sufficiently SLF throughout the middle portion of its range to a 20 degree of accuracy termed "eye accuracy," that is, to a degree of accuracy that would appear to give equal graduations by simple examination. However, Fig. 16 shows that in absolute units it departs quite markedly from SLF, sufficiently so 25 that the use of a straight line dial mechanism is impracticable over the 17% tuning range shown.

Considerable investigation has been made of the use of tapered cores or cores with various 30 profiles that could straighten out our SLF portion into a fairly high degree of accuracy over a tuning range of 8% to 10% as shown in curve F, Fig. 16, but since curve A' is drawn for the condition of the largest practical core in the 35 form of a practically solid cylinder, it will be realized that we can only shape the core by removing material, and consequently our total tuning range is less, as can be seen by examination of F. Referring back to Fig. 15, it can be seen that the SLF rapidly disappears as we reduce the amount of metal in the core, so that this method of straightening up the SLF runs against a severe limitation if we wish to obtain the maximum possible effect.

45 Curve F was obtained with a 4% taper of a cylindrical core $\frac{1}{2}$ inch long with the small end entering the coil first.

Approximately the same result was secured by 50 short sections of cylinders, cylindrical cores separated critical distances by insulating washers, and also by localized tapering of the core such as notching, and reducing diameters at various places by critical amounts. In general, no very 55 pronounced phenomena were encountered, as the core seemed to work largely on the group field, and minor detail on the core did not matter.

It is the nature of a spiral coil of only two or 60 three turns spread over a length equal to its own diameter that the turns have considerable pitch, and as a consequence the flux is by no means along the axis, but is affected by the pitch of the end turn.

An entirely different line of attack is shown 65 by the construction illustrated in Figs. 7 and 8, where a "no pitch" winding is used. Here each turn, except for a rather negligible cross-over connector, is exactly normal to the axis of the coil, and investigation showed the flux to be almost purely axial. By critical spacing of the 70 three turns shown in Fig. 8, the rate of increase of the flux can be controlled, especially of the mutual inductance between the turns. When the turns of the coil of Fig. 8 are equally spaced 75 by a distance of 125 mils (edge of one turn to

edge of the next) a tuning curve similar to dotted curve G is produced. It will be noted by comparing this curve with curve A' that whereas the latter curve slopes continually downwardly toward its center portion, the effect of the mutual inductance between the turns has been to cause the center portion of the curve to be picked upwardly to a very substantial extent, as indicated.

It has been possible to utilize this variation caused by the mutual inductance between the turns to assist in the production of SLF to the extent shown in curve H by choosing the proper distance between the coil turns and the proper core diameter.

This curve H was produced with a small spacing between the two turns on the side of the coil which the core normally enters (61 mils), and an exaggerated spacing to the next turn (125 mils). The diameter of the inside of the winding was 430 mils, and the core diameter was 365 mils to give the result shown, which is an SLF range of 22%. The core length was 500 mils, the hole through the core being 187 mils in diameter. The coil was wound with copper strap 71 mils wide and 35 mils thick.

It is believed to be possible to increase the tuning range by reducing the diameter of the coil form somewhat, but because of inability to procure special ceramic coil forms required it has not been possible for the present to investigate the problem further in this direction.

Considerable experience has shown that the straightness of curve H is adequate for use with the straight line tuning mechanism over a range of 22 megacycles, so that it is possible to use a dial of the type shown in which the dial graduations are made directly in terms of frequency.

Where it is desired to establish tuning ranges in the portion of the spectrum above 160 megacycles or so, and still maintain a high order of circuit stability by having a good sized tuning condenser, a two-turn coil must be used. It has been found insufficient merely to vary the distance between these two turns to obtain SLF, or any other desired curve, so a new variable is introduced, the choosing of different diameters of the two turns, with the turn on the entering side of the core the smaller. The coil in which turns are of different diameters is shown in Figs. 10 to 14, inclusive.

The use of a ferromagnetic core has been assumed in the above description, as well as a ferromagnetic slug. It is known that in the case of a coil intended to be used at audio frequency with an ordinary laminated iron core, that the inductance of the coil itself may be increased a rather small amount by inserting only a laminated core as, for example, ten times. If the core be then removed and the entire outside magnetic circuit closed with a shell of laminated iron, the inductance will be raised also by a similar amount, as for example, ten times. Now if the core be reinserted so that the magnetic path is completely iron, the inductance value is increased by a very large amount, such as a total of one thousand times, as there is now no air gap in the magnetic path.

It has been found this holds true in ferromagnetic circuits at frequencies of the order of 100 to 300 megacycles, but since the ferromagnetic material is finely divided and contains numerous air gaps itself, the effect is much less pronounced. While the external slug may be a complete shell, and an extended tuning range may be obtained by such a shell in combination with a movable

core, our purpose of changing the tuning slope, or rate of change of frequency for a given core displacement, is achieved by a rather small cross-section slug arranged to be brought close to, or withdrawn from, the side of the coil. This is mainly to allow for commercial tolerances in coils, condensers and tubes, and a slug of the size and disposition shown in Fig. 7 is adequate for our present purpose. While this feature of the invention has been described in connection with a coil of low inductance and few number of turns of a resonant circuit tunable over a range of ultra-high frequencies, it is equally suitable for adjusting the slope of circuits tunable within lower frequency ranges including the present broadcasting range and audio frequency ranges. The coils of such circuits may have a much larger number of turns, such as several hundred, but the effect of the outside slug is similar.

Where it is desired to precisely adjust the resonant frequency of an oscillator or other resonant circuit to a single predetermined frequency, the capacity and inductive elements of the circuit may be made to tune to this frequency as close as practical considerations permit, leaving the precise adjustment to the correct frequency to the manipulation of the slug 15. It will, therefore, be seen that a single self-contained unit, but without the movable core 12a, permits radio apparatus to be built to resonate at a single assigned frequency in a very simple, compact and stable form.

I have described what I believe to be the best embodiments of my invention. I do not wish, however, to be confined to the embodiments shown, but what I desire to cover by Letters Patent is set forth in the appended claims.

I claim:

1. A tuning coil of solenoidal form for ultra-high frequencies comprising a plurality of no-pitch turns for directing the flux along the coil axis, cross connecting means joining the ends of adjacent turns to one another to produce additive inductive effects, said connecting means extending substantially in the direction of the coil axis, and a core arranged to move axially inside said coil, the coil turns being critically spaced from one another and being of different critically related diameters in relation to the core characteristics, whereby the combined effect of the changes of self-inductance of the turns, dependent upon their respective diameters, and the mutual inductance of the turns, dependent upon their diameters and spacing, is made responsive to the core movement to produce a straight line relationship of core displacement to frequency.

2. A tuning coil of solenoidal form for ultra-high frequencies comprising a plurality of no-pitch turns for directing the flux along the coil axis, cross connecting means joining the ends of adjacent turns to one another to produce additive inductive effects, said connecting means extending substantially in the direction of the coil axis, and a core arranged to move axially inside said coil, the coil turns being critically spaced from one another and being of different critically related diameters in relation to the core characteristics, whereby the combined effect of the changes of self-inductance of the turns, dependent upon their respective diameters, and the mutual inductance of the turns, dependent upon their diameters and spacing, is made responsive to the core movement to produce a straight line relationship of core displacement to frequency, a massive ferromagnetic slug not substantially

shorter than the coil, means supporting the slug alongside the coil with capacity for adjustment transversely of the coil axis, and means for securing the slug in selected positions of adjustment relative to the coil, whereby the slope of the tuning curve may be adjusted while maintaining the straight line character thereof.

3. An inductance varying core assembly, adapted to cooperate with an inductance coil, said core assembly comprising a hollow cylindrical core, a ceramic supporting rod extending through the core, a member unitary with the rod and constituting an enlargement of the rod at one end thereof, formed with plane end faces normal to the rod axis, one of said end faces constituting a datum plane and the other constituting a shoulder at a fixed predetermined distance from the datum plane, and parallel to it, for engaging the core and controlling the position of the core relative to said datum plane, the core being mounted freely on the rod, a spacer sleeve means mounted freely on the rod at the opposite end of the core from said shoulder, and resilient means affixed to the end of the rod remote from the datum plane for transmitting pressure through the spacer sleeve means to press and maintain the core in engagement with said shoulder.

4. In combination, a coil unit and a core assembly cooperative therewith said core assembly comprising a hollow cylindrical core, a ceramic supporting rod extending through the core, a member unitary with the rod and constituting an enlargement of the rod at one end thereof, formed with plane end faces normal to the rod axis, one of said end faces constituting a datum plane and the other constituting a shoulder at a fixed predetermined distance from the datum plane, and parallel to it, for engaging the core and controlling the position of the core relative to said datum plane, the core being mounted freely on the rod, spacer sleeve means mounted freely on the rod at the opposite end of the core from said shoulder, and resilient means affixed to the end of the rod remote from the datum plane for transmitting pressure through the spacer sleeve means to press and maintain the core in engagement with said shoulder, said spacer sleeve means including a sleeve element immediately adjacent the core and within the coil unit of slightly greater diameter than the core, whereby rubbing of the core against the coil unit is prevented.

5. In combination, a hollow cylindrical core adapted to tune a resonant circuit, actuating means therefor including a metallic push rod, a ceramic supporting rod extending through the core, a ceramic spacer member unitary with the supporting rod and constituting an enlargement of the supporting rod at one end thereof, formed with plane end faces normal to the rod axis, one of said end faces constituting a datum plane and the other constituting a shoulder at a fixed predetermined distance from the datum plane and parallel to it for engaging the core and controlling the position of the core relative to said datum plane, means maintaining the core in intimate abutting relation to the shoulder, and means for maintaining the end face of the spacer which constitutes the datum plane in intimate abutting relation to an end face of the actuating push rod.

6. In combination, a hollow cylindrical core adapted to tune a resonant circuit, actuating means therefor including a metallic push rod, a

ceramic supporting rod extending through the core, a ceramic spacer member unitary with the supporting rod and constituting an enlargement of the supporting rod at one end thereof, formed with plane end faces normal to the rod axis, one of said end faces constituting a datum plane and the other constituting a shoulder at a fixed predetermined distance from the datum plane and parallel to it for engaging the core and controlling the position of the core relative to said datum plane, means maintaining the core in intimate abutting relation to the shoulder, and means rigidly attaching the spacer to the push rod for establishing and maintaining the spacer in coaxial relation to the push rod and for maintaining the end face of the spacer which constitutes the datum plane in intimate abutting relation to an end face of the push rod.

7. An inductance varying core assembly adapted to cooperate with a plurality of coaxial inductance coils, comprising, in combination, a first hollow cylindrical core, a ceramic supporting rod extending through the core, a ceramic member unitary with the rod and constituting an enlargement of the rod at one end thereof, formed with plane end faces normal to the rod axis, one of said end faces constituting a datum plane, and the other constituting a shoulder at a fixed, predetermined distance from the datum plane and parallel to it, for engaging the core and controlling the position of the core relative to said datum plane, the core being mounted freely on the rod, spaced sleeve means comprising a series of spacer sleeve elements mounted freely on the rod at the opposite end of said core from said shoulder, and resilient means to press and maintain the core in engagement with said shoulder, one of the spacer sleeve elements consisting of a second hollow cylindrical core, and another of the spacer sleeve elements constituting a metallic bearing sleeve located between the first and second cores.
